SPACE HEATER

Neil R. Gienke, Cleveland, Ohio, assignor to Hupp Corporation, Cleveland, Ohio, a corporation of Virginia

Application April 4, 1957, Serial No. 45,590

Term of patent 7 years

(Cl. D81—19)

The single figure is a perspective view illustrating the front and one end of a space heater embodying my new design, the opposite end of the heater being identical to the end illustrated and the back of the heater being a flat rectangular sheet.

I claim:

The ornamental design for a space heater, substantially as shown and described.
